(57) **CLAIM**

The ornamental design for a cart-based ultrasonic diagnostic equipment, as shown and described.

DESCRIPTION

FIG. 1 is a first perspective view of a cart-based ultrasonic diagnostic equipment;

FIG. 2 is a second perspective view of the cart-based ultrasonic diagnostic equipment;

FIG. 3 is a front view of the cart-based ultrasonic diagnostic equipment;

FIG. 4 is a rear view of the cart-based ultrasonic diagnostic equipment;

FIG. 5 is a left side view of the cart-based ultrasonic diagnostic equipment;

FIG. 6 is a right side view of the cart-based ultrasonic diagnostic equipment;

FIG. 7 is a top view of the cart-based ultrasonic diagnostic equipment;

FIG. 8 is a bottom view of the cart-based ultrasonic diagnostic equipment;

FIG. 9 is a partially enlarged view I in FIG. 1;

FIG. 10 is a partially enlarged view II in FIG. 1;

FIG. 11 is a partially enlarged view III in FIG. 1;

FIG. 12 is a partially enlarged view IV in FIG. 2; and,

FIG. 13 is a partially enlarged view V in FIG. 2.

The broken lines in the drawings depict portions of the cart-based ultrasonic diagnostic equipment that form no part of the claimed design.
